UNITED STATES PATENT OFFICE

152,349

DESIGN FOR A HARP

Juanita Miller, Oakland, Calif.

Application April 8, 1947, Serial No. 138,220

Term of patent 14 years

(Cl. D56—1)

To all whom it may concern:

Be it known that I, Juanita Miller, a citizen of the United States, residing at 3152 Joaquin Miller Road, Oakland, in the county of Alameda and State of California, have invented a new, original, and ornamental Design for Harps, of which the following is a specification, reference being had to the accompanying drawing, forming part thereof.

In the drawing

Fig. 1 is a front view of a harp, showing my new design;

I claim:

The ornamental design for a harp, as shown.

JUANITA MILLER.
